United States Patent Office

Des. 207,262
Patented Mar. 28, 1967

207,262

STUDENT'S CHAIR AND DESK

Robert A. Maurer and Leslie R. Maurer, East Palestine, Ohio, assignors to The Kenmar Manufacturing Company, East Palestine, Ohio, a corporation of Ohio

Filed Jan. 24, 1966, Ser. No. 728

Term of patent 14 years

(Cl. D33—11)

FIGURE 1 is a perspective view showing the front, top and one side of the student's chair and desk;

FIGURE 2 is a perspective view showing the front, side and bottom of the student's chair and desk;

The side not shown is a substantial duplicate of the side illustrated. The back is substantially plain.

We claim:

The ornamental design for a student's chair and desk, as shown and described.
